FIREPLACE TONGS

Alvin M. Cahan, 84 Carlton Road, Waban, Mass.

Filed Dec. 11, 1962, Ser. No. 72,808

Term of patent 14 years

(Cl. D81—24)

BEST AVAILABLE COPY

FIG. 1 is a perspective of one embodiment of fireplace tongs showing my new design.

FIG. 2 is an elevation of the tongs for FIG. 1 looking at a side thereof.

FIG. 3 is an elevational view of the tongs of FIG. 1 looking toward the edge thereof.

FIG. 4 is a cross sectional view of the embodiment of FIG. 1 taken on line 4-4 of FIG. 2.

FIG. 5 is a perspective view of another embodiment of the fireplace tongs shown in FIG. 1.

FIG. 6 is a fragmentary side elevation of the embodiment shown in FIG. 5.

FIG. 7 is a fragmentary front elevation of the embodiment shown in FIG. 5.

I claim:

The ornamental design for fireplace tongs, as shown and described as shown.
